US0D1087071S

(12) **United States Design Patent** (10) Patent No.: **US D1,087,071 S**
(45) Date of Patent: ** Aug. 5, 2025

(54) **ELECTRONIC MUSICAL INSTRUMENT**

(71) Applicant: **Superlative Instruments LLC**,
Cambridge, MA (US)

(72) Inventor: **Benjamin Stamas**, Cambridge, MA
(US)

(73) Assignee: **Superlative Instruments LLC**,
Cambridge, MA (US)

(**) Term: **15 Years**

(21) Appl. No.: **29/941,579**

(22) Filed: **May 10, 2024**

(51) LOC (15) Cl. **14-03**

(52) U.S. Cl.

USPC **D14/217**

(57) **CLAIM**

The ornamental design for the electronic musical instrument, as shown and described.

DESCRIPTION

FIG. 1 is a front perspective view of the electronic musical instrument showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is the top plan view thereof; and,

FIG. 7 is the bottom plan view thereof.

The broken lines depict portions of the electronic musical instrument that form no part of the claimed design.

1 Claim, 5 Drawing Sheets
